METHOD FOR REGENERATING CATALYST BY COMBUSTION

James Guthrie, Sarnia, Ontario, Canada, assignor to Esso Research and Engineering Company, a corporation of Delaware

Application March 28, 1952, Serial No. 279,061

1 Claim. (Cl. 252—417)

This invention relates to catalytic processes and relates particularly to the use of gas turbines for supplying air or the like to a catalyst regenerator. Most specifically, it relates to a process and apparatus wherein a gas turbine is so integrated in a petroleum cracking system that the turbine exhaust gas is used as the air required for combustion of the carbonaceous catalyst deposit in a "fluid" catalyst regenerator.

In recent years catalytic cracking processes have gained prominence in the conversion of crude petroleum, and "fluid" catalytic cracking has assumed a particularly important position in the petroleum industry. In all catalytic cracking processes, whether in a fixed bed, a moving bed, or turbulent fluidized bed, hydrocarbon vapors are contacted with catalyst at suitable temperatures whereby heavy molecules are cracked to yield more valuable lighter products, especially gasoline. However, during such cracking the catalyst gradually becomes covered by a carbonaceous deposit which reduces the catalytic activity of the catalyst. As a result, after a certain residence time in the cracking zone the catalyst must be regenerated by combustion of the carbonaceous deposit.

Such regeneration represents one of the major steps in modern catalytic cracking processes and especially in "fluid" operations usually requires a larger vessel than the principal cracking reaction. The cost of the required air compressors, usually driven by electric motors or by steam turbines, as well as the necessary boilers or electrical power system, constitute one of the large cost items in the operation of such catalytic cracking systems. Consequently the regeneration stage often limits the overall cracking capacity of a given commercial unit. Furthermore, conventional units usually require auxiliary burners which are used for heating the air whenever the regeneration step is first started.

Heretofore some improvement in economy has been obtained by using the hot exhaust gas from catalyst regenerators to drive a flow-type gas turbine. However, this modification did not in any way affect the major investment required for compressors and incidental prime movers needed to feed air into the regenerator initially, nor did it eliminate the need for auxiliary burners required in starting up the operation of a conventional catalyst regenerator.

Accordingly, it is an object of this invention to improve the operation of catalytic cracking processes, and particularly to reduce capital expenditure. Another object is to provide a cracking plant which can be operated without requiring the conventional air compressors and prime movers needed to drive such compressors. Still other objects as well as the nature of the present invention will become apparent from the subsequent description as well as the attached drawing wherein:

Fig. 1 is a diagrammatic illustration of a system comprising a combustion gas turbine which can be used according to this invention for supplying the air requirements of a catalyst regenerator;

Fig. 2 is a diagrammatic illustration of a similar but

more elaborate system containing a heat exchanger for extracting heat from the regenerator combustion gases as well as an electric power generator, as a result of which a "fluid" catalytic cracking unit may be made still more economical both with respect to air requirements and power for auxiliaries.

In the subsequent description it will be understood that, unless otherwise stated, whenever the expressions "gas turbine" or "turbine" are used, a gas turbine of the 10 "combustion" type rather than of the "flow" or steam type is meant. In the latter case, for instance, steam must first be brought up to the desired pressure and temperature in an auxiliary power plant before it is fed to and expanded through the turbine where power is generated. 15 In contrast, in a gas turbine air is usually compressed by an axial flow compressor, fuel is injected into the compressed air and burned in a combustion chamber, the hot combustion gases are expanded through the turbine proper, and discharged to the atmosphere. Where air is 20 expensive because of required purification, a so-called closed cycle may be used wherein the exhausted air may be used over again.

The gas turbine itself drives its own compressor and any excess power may be used to drive a useful load.

25 While the combustion gas turbine requires some external means such as an electric motor to start it and get it up to partial speed, it is otherwise a completely self-contained power plant. It is not necessary to make any steam or condense it.

30 Thermal efficiency of a gas turbine to its output shaft may range from about 15 or 17 percent upward, depending on permissible maximum temperature and on various modifications of its operation. For instance, when some of the heat of the exhaust gases is utilized for pre-heating

35 the compressed air, the thermal efficiency may be raised to some 20 to 30 percent. Thermal efficiency may also be increased by compressing the air in two stages, with water cooling between stages. This arrangement makes the second-stage compressor smaller and more efficient, 40 more than compensating for the heat lost.

For flexibility and economy, the turbine may be a two-shaft or multiple-shaft unit, rather than a single-shaft unit. For instance, in a two-shaft unit the turbine may be split into a high-pressure and a low-pressure turbine unit 45 in such a fashion that the exhaust from the high-pressure unit drives the low-pressure unit. In such a case the high-pressure turbine may be used entirely to drive the compressor and the mechanically independent low-pressure turbine may be connected to the output shaft; or 50 when a two-stage compressor and intercooler are used, the high-pressure turbine may drive both the high-pressure compressor and the output shaft, while the low-pressure turbine may drive the low-pressure compressor. The main advantage of the multi-shaft turbine is its ability 55 to have its compressor speed adjusted to give the needed air flow, independently of the output speed.

Still other modifications and variations in the mechanical arrangement and operation of the gas turbine, as such, are well known in the art. They have been summarized above only incidentally to the description of the present invention, the essence of which lies in the combination of the gas turbine with a catalyst regenerator in such a fashion that the turbine exhaust serves to supply air to the catalyst regeneration zone as described hereafter.

Referring specifically to Figure 1 of the drawing, atmospheric air or other combustion supporting gas from line 1 may enter axial flow compressor 2 where it is compressed to about 60 to 200 p. s. i. gauge, or preferably 90 to 150 p. s. i. gauge, or any other pressure required for the particular power output and desired conditions of the turbine exhaust gases. The compressed

air may pass via line 3 through heat exchanger 4 where it may be heated to about 300 to 600° F. by the hot turbine exhaust gases passing through line 5. The hot compressed air is then passed to turbine combustion chamber 6 where it is mixed with a fuel such as diesel oil, burner fuel, hydrocarbon gas or powdered coal injected through line 7. According to common practice the air is used in at least about 3 to 6 times the theoretical amount required to burn the fuel in the combustion chamber. The hot excess air and combustion products pass from combustor 6 through line 8 to turbine 9 at a temperature of about 800 to 2000° F., preferably 1200 to 1500° F., depending on the inherent limitations of the metal used in the turbine. On expansion through turbine 9 enough power is produced to drive both air compressor 2 by means of shaft 10 and electrical generator 11 or any other load attached to output shaft 12. In normal operation the turbine may be operated at a temperature to just operate the compressor 2 and have no net power output or conversely, only a fraction of the total power produced in turbine 9 may be used for driving the compressor 2, the balance of power generated being available to drive any other load. Shaft speeds may be of the order of about 4000 to 10,000 or more revolutions per minute.

The expanded oxygen-rich exhaust gases pass from turbine 9 through line 5 at a temperature of about 400 to 900° F. and preferably at only slightly superatmospheric pressure, e. g. 15 to 25 p. s. i. gauge, as may be required for catalyst regeneration. Finally the gas may be cooled to about 400 to 600° F. in heat exchanger 4 to obtain optimum conditions of temperature and pressure for feeding to a conventional catalyst regenerator 17 wherein it serves to oxidize carbonaceous deposits off spent catalyst particles. For instance, spent catalyst particles may be withdrawn from a conventional "fluid" catalytic cracking reactor 26 via standpipe 27 and mixed into the turbine exhaust gases passing through line 15. The resulting mixture of catalyst particles and air then may pass in the form of a suspension through riser 16 into regenerator 17, where carbonaceous deposits are burned off the catalyst at temperatures between about 850 and 1200° F. Because of the relatively large diameter of vessel 17, the mixture of catalyst and gas forms a dense turbulent liquid simulating bed of solids in the lower part of vessel 17 with a more dilute phase thereabove, as is well known per se. Regenerated catalyst particles may be withdrawn from vessel 17 via standpipe 18 and returned to reactor 26 together with fresh cracking feed such as gas oil or the like. Hot flue gas may be withdrawn overhead, preferably after passage through a cyclonic dust separator 19, and passed via line 20 to a waste heat boiler 21 for recovering additional heat.

From the foregoing it will be seen that a plant designed as described above avoids any need for separate air compressors to supply air to the catalyst regenerator, since the oxygen-rich exhaust from the turbine is well suited for use in the regenerator.

Furthermore, a plant designed according to the present invention has the advantage of eliminating any need for an auxiliary burner such as is otherwise required in conventional catalytic cracking units. Specifically, when a "fluid" catalytic cracking plant is first started, it is essential that the air fed to the regenerator be heated to about 650 to 700° F. before any oil can be added to the reactor. This heat during start-up has been heretofore obtained through the use of auxiliary burners which have represented a substantial portion of the total investment required, although the actual need for such burners is limited to a very small percentage of the operating life of the principal cracking unit. The present invention avoids the need for any such auxiliary burners since the turbine exhaust gases in line 15 of Fig. 1 may themselves be at sufficiently high temperatures, especially if at least a portion of the gases is allowed to bypass heat exchanger 4 via line 14 during the start-up period.

Another still more efficient embodiment of the invention is illustrated in Fig. 2. Referring to Fig. 2, atmospheric air at about 80° F. may be introduced into the system via line 201 which leads to low-pressure compressor 202. In compressor 202 the air may be compressed and its temperature raised thereby to around 300 to 350° F. This air may then be passed via line 203 through intercooler 204 wherein it may be cooled to about 90 or 100° F. by heat exchange with cooling water passing through line 205. The cooled compressed air may then be passed to high-pressure compressor 206 where it is compressed to a pressure preferably in excess of 90 p. s. i. gauge and its temperature raised to about 350° F. or more.

This hot compressed air may then be passed via line 207 consecutively through heat exchangers 208 and 209 where it acquires heat from other gas streams later to be described. Thus the compressed gas may be heated to at least 600 or 800° F. before introduction into combustor 210. In combustor 210 the compressed air is used to burn fuel injected through line 211. Again, a large excess of air is used as described earlier in connection with Fig. 1 and the resulting oxygen-containing combustion gas may be at a temperature of about 1300° F. or higher if the turbine metal permits. This hot compressed gas is then passed via line 212 to high-pressure turbine 213 through which it is expanded to an intermediate pressure, e. g. 10 to 50 p. s. i. gauge or such other pressure as may be desired for catalyst regeneration. The power generated in turbine 213 may be used to drive high-pressure compressor 206 by means of shaft 214 as well as a useful load such as electric power generator 215. The shaft speed in this particular instance may be between about 8500 and 9000 R. P. M. From turbine 213 the amount of partially expanded gas required for catalyst regeneration is preferably withdrawn via line 240 or from an analogous intermediate stage passed through cooler 241 before continuing into regenerator vessel 220 where it is used to burn coke-like deposits off spent catalyst particles in the same manner as described earlier in connection with regenerator 17 of Fig. 1. However, whereas the hot flue gas was used for steam generation in Fig. 1, in the presently illustrated preferred embodiment the hot flue gas from regenerator 220 is passed via line 221 through heat exchanger 209 where it transfers heat to the incoming compressed air, thus contributing towards a further fuel saving in the operation of the process. Finally, the flue gas from exchanger 209 is exhausted to the atmosphere, or may still be passed through a waste heat boiler for recovery of additional heat therefrom.

The amount of partially expanded gas not required for regeneration may be passed from high-pressure turbine 213 to low-pressure turbine 217 via line 216. In turbine 217 it is further expanded preferably to atmospheric pressure, yielding additional power and high efficiency. The power thus produced in low-pressure turbine 217 may be used to drive low-pressure compressor or any other load via shaft 218 which may have a speed of about 7000 to 7500 R. P. M.

The atmospheric gas exhausted from turbine 217 may be passed at about 800 to 900° F. via line 219 through heat exchanger 208 and finally vented through line 250, or at least a portion of it may be recycled to low-pressure compressor 202 via line 251 and further cooler 252. In exchanger 208 some of the heat contained in the exhaust gas may be used to preheat the freshly compressed air in line 207.

On the other hand, if no net power output is contemplated in the system, or at any rate if all the air passing through the turbines is required for catalyst regeneration, then the exhaust pressure of the low-pressure turbine is set at 15 to 20 p. s. i. gauge or whatever pressure may be desired in catalyst regenerator 220. In such a case no gas is drawn off at any intermediate turbine stage such as line 240. Instead, all the air exhausted at

the desired pressure from low-pressure turbine 217 is passed through line 219 and heat exchanger 208 into catalyst regenerator 220. The intermediate pressure between turbine stages may of course be higher here than in the alternative design wherein the terminal exhaust gas is at substantially atmospheric pressure. For instance, where the exhaust from the low-pressure turbine is at about 15 p. s. i. gauge, the intermediate turbine pressure may be between about 35 and 70 p. s. i. gauge, depending on the pressure of the high-pressure stage and other factors well known in turbine design. Also, it will be understood that where the turbine exhaust is at a higher temperature than the regeneration flue gas, the position of heat exchangers 208 and 209 may be reversed so that the compressed air feed is preheated first by the flue gas and then by the turbine exhaust.

Having described the general nature of the invention as well as several specific embodiments thereof, it will be understood that still other embodiments and modifications are possible without departing from the scope hereof. For instance, it is entirely feasible to pass a portion of the compressed air from the compressor directly to the turbine, by-passing the combustor as shown at 230 in Fig. 2, instead of feeding all the air through the combustor. Likewise, it may often be advantageous to have a multiple-stage combustor instead of the single stage shown, particularly where complete fuel clean-up is important.

The invention is particularly pointed out and claimed as follows.

I claim:

In a process for regenerating spent solid catalyst containing a carbonaceous deposit thereon, the improvement which comprises compressing atmospheric air in at least one compression stage to a pressure of from about 60 to
